Primary Examiner — Jennifer Rivard(74) *Attorney, Agent, or Firm* — QuickPatents, Inc.; Kevin Prince**CLAIM**

What is claimed is the ornamental design for a lighter clip, as shown and described.

DESCRIPTION

FIG. 1 is an exploded perspective view of a lighter clip, showing the new design in a straight configuration; FIG. 2 is a front elevational view thereof; FIG. 3 is a rear elevational view of FIG. 2; FIG. 4 is a front elevational view thereof, illustrated in a bent configuration; FIG. 5 is a left-side elevational view of FIG. 2; FIG. 6 is a right-side elevational view of FIG. 2; FIG. 7 is a top plan view of FIG. 2; and, FIG. 8 is a bottom plan view of FIG. 2. The broken lines showing a cigarette and lighter in FIG. 1 are included for the purpose of illustrating the invention in use, and form no part of the claimed design.
